UNITED STATES PATENT OFFICE.

WILLIS E. PHILLIPS, OF COLBRAN, COLORADO.

WOODEN-STAVE PIPE.

No. 923,294.

Specification of Letters Patent.

Patented June 1, 1909.

Application filed June 10, 1908. Serial No. 437,788.

To all whom it may concern:

Be it known that I, WILLIS E. PHILLIPS, a citizen of the United States, residing at Colbran, in the county of Mesa and State 5 of Colorado, have invented a new and useful Wooden-Stave Pipe, of which the following is a specification.

This invention relates to pipes for transporting liquid under pressure; and has for 10 its object to produce a pipe made of a number of straight flat wooden staves assembled with their edges in contact to form a tubular structure of polygonal outline in cross section.

15 Another object of the invention pertains to the key stave which serves the double function of forming one of the sides of the pipe and as a means to hold the ends of the hoops or bands.

20 A further object of the invention is directed to the joints between the staves whereby they are made watertight, however great the internal pressure against the staves.

With these and other objects in view, the 25 invention consists of the novel construction combination and arrangement of parts hereinafter described and claimed, and illustrated in the accompanying drawings, in which—

30 Figure 1 is a side view of one end of a pipe constructed in accordance with this invention; Fig. 2, a cross sectional view of the same on the line 2—2 of Fig. 1; Fig. 3 a detail view in cross section of a part of a pipe showing the effect of internal pressure 35 on the staves and joints; Fig. 4 a perspective view of one end of a stave; Fig. 5 a perspective view of a metal reinforce for the key stave for one hoop or band; and Fig. 6 a like view of a reinforce of indefinite length 40 where the hoops or bands are close together.

Similar reference characters are used for the same parts in all the figures.

In the drawing, 1 indicates the ordinary 45 staves and 2 the key stave. The ordinary staves 1 are made with straight parallel sides and beveled edges 3 the angles of which depend upon the number of sides of the polygonal pipe, the inclination being such 50 that when assembled the beveled edges of the staves will be in close contact throughout their width. The ordinary staves 1 are made straight instead of being bent or coopered into a curved form because they can be 55 manufactured more cheaply and with greater economy of wood than coopered staves which

require thicker lumber in order that the curved shape may be given them, thus causing a great waste of wood, and besides this, the cost is further increased as it is necessary 60 to use expensive planing and shaping machinery to shape the staves whereas, with straight sided staves, they can be easily, quickly and cheaply made in any saw mill.

The key stave 2 is much thicker than the 65 ordinary staves 1 and projects beyond the outer surfaces of the pipe for its entire length, its exterior edges being slightly inclined from the surface of the pipe inwardly to its outer side parallel to its straight inner 70 side.

Around the pipe at suitable distances apart are placed hoops 5 of circular form and therefore do not touch the staves except at the angles, corners or junctions between 75 staves. The ends 6 of the hoops 5 are not joined, but made straight so that their ends may pass each through a separate hole bored at an angle transversely in the outer portion of the key stave 2 and be held in place 80 around the pipe and drawn tightly against the angles or corners thereof by means of nuts 7 screwed on the ends of each hoop. The straight end 6 of the hoops are tangents thereof and hence, cross each other as they 85 pass through the key stave the edges of which are made perpendicular to the threaded extremities of the hoop ends so that the fastening nuts 7 will bear squarely on the key stave. The pressure exerted by the nuts 90 when drawing the hoops to place is not great enough to change the circular shape of the hoop but it may be sufficient to slightly crush the corners or angles of the pipe, and therefore secures a longer bearing thereon. 95

The distance between the hoops depends on the amount of pressure the pipes are designed to withstand. If they be subjected to high pressure the hoops will be placed close together, but when employed as non-pres- 100 sure pipes only, a few hoops only are needed.

When the pipe is to withstand a heavy pressure, a metal reinforcing plate 8 is placed over the key stave at each hoop, hugging the stave closely on top and exposed 105 sides, and provided with holes 9 registering with the holes in the key stave for the ends of the hoop to pass through. If preferred a continuous or channel iron reinforce 10 may be employed instead of numerous single 110 reinforce plates 8, and under certain circumstances, the channel iron reinforce is

preferred. The reinforce plate 8 is fastened in place by a bolt 11 passing through the key stave 2 and the plate, and held by a nut 12. Similar fastening means are employed 5 to hold the reinforce 10.

Before assembling the staves, the number of which is not limited but varies with the size of the pipe and the pressure to be sustained, the joining edges only, having been 10 beveled, are soaked in water to temporarily toughen the fiber, and then by means of a special tool, the dampened edges are combed against the grain when possible to raise a "nap" of wood fiber resembling wool. After 15 assembling the staves to form the pipe, and the hoops applied, the "wooled" edges of the staves are drawn closely together and form strainers, gathering silt and solid matter in the water passing through the pipe which material is forced deeper into the joints by 20 the pressure of the water and, being held by the "wooled" or "napped" surfaces of the staves, self-calking joints are formed in which silt becomes the calking medium and 25 the "wood wool" the medium for retaining it.

As the staves become saturated they expand and the angles or corners of the pipe section will thus be forced outward against 30 the practically non-yieldable hoops. That portion of the wood immediately beneath the hoops will be crushed by the pressure and this will give each hoop a longer bearing on the stave and the pipe will thus be 35 more firmly held in proper shape.

When the pipe is subjected to very high pressure the staves are bulged or forced outwardly, see Fig. 3, toward the hoops, the pressure tending to curve each stave like a 40 coopered stave. This increases the length of the crush bearings, that is, the bearings between the hoops and the staves, so that the center of the staves will never be forced quite to the hoops. This change in shape 45 of the staves will, naturally slightly open the joints between the staves within the pipe, which will quickly fill up with silt, and be forced closer together on the outside, thus effectually calking the joints. The 50 greater the pressure the tighter the joint. The key stave 2 as previously stated is also made of wood and of greater thickness than the ordinary staves to give support to the ring hoops which unite the staves to form 55 a polygonal pipe. This stave, therefore, takes the place of the usual metal fastenings employed to fasten the ends of the hoops and, being made of wood it is cheaper and serves not only as a medium for secur-

ing the ends of the hoops but performs the 60 functions of a stave.

What is claimed is:—

1. A polygonal pipe formed of staves having flat parallel sides and beveled edges, circular hoops bearing on the corners only 65 of said pipe, and a key stave to which the ends of said hoops are fastened.

2. A polygonal pipe formed of staves having flat parallel sides and beveled edges, circular hoops bearing on the corners only 70 of said pipe to hold said staves in contact, and a key stave thicker than the other staves to which the ends of said hoops are fastened.

3. A polygonal pipe formed of staves having flat parallel sides and beveled edges, 75 circular hoops bearing on the corners of said pipes, a key stave forming a part of the pipe and made thicker than the other staves through which the ends of said hoops pass, and means for holding and tightening 80 said hoops around the staves.

4. A polygonal pipe formed of staves one of which is thicker than the others and all having flat parallel sides and beveled edges, circular hoops bearing on the corners only 85 of the thin staves and passing through the thicker stave, a reinforcing plate on the exterior of said thick stave through which the ends of said hoops extend and tightening 90 means upon the ends of the hoops. 90

5. A polygonal pipe formed of staves with flat parallel sides and beveled edges, circular hoops bearing on the outer corners only of 95 said staves, and holding them in forcible contact and tightening means for said hoops, said stave edges being roughened to permit the entrance and retention of silt from within the pipe for forming a tight joint between the staves.

6. A wooden pipe formed of flat staves 100 having their edges beveled and circular hoops for holding the staves forcibly in contact, one of said staves being thicker than the others for the attachment of the encircling hoops. 105

7. A wooden pipe formed of staves having their edges roughened to permit the entrance of silt between said roughened edges and retained therein by internal pressure to form a packing. 110

In testimony that I claim the foregoing as my own, I have hereto affixed my signature in the presence of two witnesses.

WILLIS E. PHILLIPS.
